PIN AND CLASP FOR JEWELRY

Maximilian C. Meyer, Brooklyn, N. Y.

Application December 22, 1948, Serial No. 66,725

2 Claims. (Cl. 24—88)

1

This invention relates to a novel two piece jewelry clasp and to combinations of the clasp with ornamental chains or strings which are so constructed that the two clasp parts may be attached to each other to form a necklace or bracelet or may be attached separately to an article of apparel and be worn as a chatelaine.

An object of this invention is to provide a novel clasp for necklaces and bracelets.

Another object of the invention is to provide a novel two part clasp in which the separate parts of the clasp have means for attaching onto wearing apparel.

Another object of the invention is to provide a novel two part clasp, each part of which has means enabling it to be attached to articles of apparel, purses, leather goods, etc., at least one of which means cooperates with other structure on the other part to clasp the two parts together when desired.

These objects and others ancillary thereto are obtained by providing each of the parts of a two part jewelry clasp with a plural pronged pin, in addition providing the first of the parts with a stirrup loop adapted to be fitted over and securely held by the pin mechanism of the second part and yet so constructed as not to interfere with the operation of the pin mechanism on the first part.

The pin mechanisms preferably take the shape of a plural pronged fork and the points of the prongs are preferably turned inwardly toward the back of the device. The forked prongs on the first or stirrup containing part are held by a shaft running transversely to the base thereof and the stirrup means is pivotally mounted on the same shaft. The forked prongs of the second part are pivotally mounted on a shaft which is held in spaced relation to the back of the part so that the stirrup can be slipped over the forked prongs and held securely behind the shaft on which the prongs are held by the ears or other means which connect the prong containing shaft to the back of the second part.

Each of the parts contains eyelets or other means for attaching a string, thread, chain or other linear flexible element thereto. The term "string" as used in the specification and claims is intended to include all such linear flexible elements which are either decorative, per se, and/or are adapted to hold decorative elements such as beads, pearls, charms, pendants, locks, etc.

The novel features characteristic of this invention are set forth with particularity in the

5 appended claims. The invention itself, however, both as to its organization and its method of operation, together with additional objects and advantages thereof, will best be understood from the following description of specific embodiments when read in connection with the accompanying drawings in which:

Figure 1 is a back-view of one type of the new two-part clasp combined with strings of beads and employed as a necklace.

Figure 2 is a view illustrating how the device of Figure 1 is worn as a chatelaine.

Figures 3a and 3b are views of the two parts 10 and 11 of the clasp as seen from the attaching ends 15 thereof.

Figures 4a and 4b are side-views of the two parts ready to be attached together.

Figure 5 is a view of the combined parts of the clasp.

20 Figure 6 is a detail view of the stirrup containing part of Figures 3b and 4b.

Each part 10 and 11 of clasp shown in the drawing has two eyelets 12, 13, 14 and 15 each adapted to support the end of a chain, a wire or 25 a thread containing, if desired, other decorative objects such as beads, pearls, charms, pendants, etc. A thread or string 20 is shown connected to eyelets 12 and 15 and a string 21 is shown connected to eyelets 13 and 14. The strings 20 and 21 as shown, are strung with beads or pearls 22, 22. The eyelets 12, 13 are formed in the metal backing 30 of part 10 and the eyelets 14 and 15 are formed in the metal backing 31 of part 11. Soldered to the back 30 is a U-shaped strip 34, the sides 37 and 36 of which form ears to contain the bearings for the shaft 38 to which the pin holding clamp 39 is attached. Extending between the ears 37 and 36 is also a cup shaped spring 35 held in place by upturned flanges 52, 53, 54 and 55. This spring 35 is preferably separately formed and inserted between the loops 32 and 33 but it may be integral with, but indented from, the bottom part of the U-shaped strip 34. The pin-holding clamp member 39 is crimped around the shaft 38 on one side and on the two sides perpendicular to the shaft 38 it is crimped about the pins 40, 41. The pointed tips 42, 43 of the pins 40, 41 are preferably bent inwardly as shown.

45 The part 11 as shown in Figures 3b and 4b has structure 34' to 42' which corresponds to parts 34—42 of Figures 3a and 4a except that in the part 11 the shaft 38' extends beyond the ends of the ears 36', 37' and carries a pivotally attached stirrup holding means 50. This stirrup

means 50 is adapted to fit closely over the pins 40', 41' when the part 11 is to be fastened by attaching the pins 40', 41' to a garment, leather article or other fabric material. The stirrup 50 however is adapted to be looped over the pins 40, 41 and the ears 36, 37 of member 10. The clamping strip 51 of the pin clamping member 39 also serves to hold the stirrup member 50 in place about the ears 36, 37 of the part 10 (see Figure 5).

The portion of the clamping members 39, 39' which extend around the shafts 38, 38' contains an integral projection adapted to bear against the cup shaped spring 35 or 35' as the pins and clamping member 39 or 39' are rotated so that the pins snap into the closed position of Figures 1 and 5. When the clamping members 10 and 11 are attached to each other the spring 35 together with the pressure of the body of the wearer against the pins 40, 41 prevents the stirrup member from coming off. The lever action of the second kind which the pins 40, 41 and the pin clamp 39 exert against the stirrup 50 with the shaft 38 as the fulcrum, is considerable. By attaching a plurality of strings 20, 21 or chains to the clasps the tendency for the clasp to turn wrong side outward when it is worn as a necklace or bracelet is diminished.

The invention provides an article of jewelry which may be worn as a chatelaine or similar decorative attachment for a dress, coat, purse, etc. or since the ends are fastenable it may be worn as a necklace or bracelet depending on the length of the attached chains or strings. The two parts are easily attached together and in spite of the ease of attachment are securely held against separation.

I claim:

1. A two-part dual-function jewelry clasp comprising a first part and a second part, said first part containing means adapted to hold the end of at least one string and having a substantially

flat back containing two ears extending substantially perpendicularly therefrom, means holding a plurality of pin elements pivotally supported from said ears, said second part containing means adapted to hold the end of at least one string, pin elements adapted to fasten the part, per se, to an article of wearing apparel, and, in addition, a stirrup shaped holding means adapted to cooperate with the ears and pivotally mounted pin elements of said first part to securely attach the second part to said first part.

2. A two-part dual-function jewelry clasp comprising a first part and a second part, said first part containing means adapted to hold the end of at least one string and having a substantially flat back containing two ears extending substantially perpendicularly therefrom, means holding a plurality of pin elements pivotally supported from said ears, said second part containing means adapted to hold the end of at least one string and having a substantially flat back containing means for pivotally supporting a shaft, a shaft in said supporting means, pin holding means attached to said shaft, a stirrup shaped holding means pivotally supported from said shaft, said stirrup shaped holding means adapted to fit about the said ears of said first part and adapted to be held in position by the pin holding means of said first part.

MAXIMILIAN C. MEYER.
